UNITED STATES PATENT OFFICE.

ALLEN B. NORTON, OF CLEVELAND, OHIO, ASSIGNOR TO ALUMINUM COMPANY OF AMERICA, OF PITTSBURGH, PENNSYLVANIA, A CORPORATION OF PENNSYLVANIA.

MOLD.

Application filed June 22, 1927. Serial No. 200,526.

This invention relates to permanent molds such as are used in casting metal. The mold to which it relates is particularly adapted to the production of large but relatively narrow castings, although it may be used for pieces of many other shapes.

Heretofore molds have been used for casting large flat and other narrow objects but difficulty has been experienced in that solid particles get between the mold sections and the sections otherwise become displaced and so produce castings of varying thickness, this being particularly noticeable and undesirable in very thin castings, and in castings which it is desired shall be used without machining.

I have provided a mold in which the parts are firmly retained in place and by which uniform castings are produced, and which at the same time is simple and durable in construction and quickly and easily operated.

The invention will be better understood from the description of one practical embodiment thereof, illustrated in the accompanying drawing, in which

Fig. 1 is a central longitudinal vertical section of a mold embodying the invention,

Fig. 2 is a central transverse vertical section thereof taken on the line II—II of Fig. 1, and

Fig. 3 is a plan view thereof, showing parts broken away.

The apparatus consists of a table having a flat horizontal top or mold base 1 supported by legs 2. Upon the top, and substantially centrally thereof, the mold sections are supported. The mold itself consists of two sections—a stationary lower section or drag 3, which is rigidly secured to the table top as by bolts 4, and a removable upper section or cope 5. The cope has an annular marginal flange 6 fitting a corresponding groove in the drag, the flange being interrupted to receive key 7, so that the sections may be positively located with respect to each other. The cope or upper section is diametrically split into two similar halves so that it may be easily removed from the casting before the gate is removed therefrom. The adjacent sides of the cope and drag are recessed to form the mold cavity, which in the apparatus illustrated, is shaped to form wheels, each having a hub 8, rim 9, and six spokes 10.

The mold sections are held in place during the casting operation by two clamping sections 11 and 12. These are hinged at one end

upon a post 13 and may be clamped together at the other by a bar 14 and clamp 15. The inner sides of the clamping sections are recessed to fit about the mold sections. At last one mold section is provided with a frustoconical or other tapered face 16 which is engaged by corresponding faces on the clamping sections so that the mold sections are wedged tightly together when the clamping sections are closed and anything holding the mold sections apart prevents the clamping sections from closing, and thus prevents use of the mold to form non-uniform castings. The clamping sections also hold the halves of the cope tightly together.

The inner sides of the clamping sections are recessed above the mold sections to provide suitable gate and riser cavities 17, communicating with the mold cavity.

A vertical plunger 18 extends through the table top and into the bottom of the cavity in the drag and may be moved upwardly to raise and eject a casting therefrom. The lower end of the plunger carries a block 19 having a rack formed along one side, the rack being engaged by a pinion 20 carried by shaft 21 and operated by handle 22 for actuating the ejector.

From the description of parts the operation of the mold will be fairly obvious. First the operator places the parts of the cope 5 upon the drag 3, causing flange 6 to engage with its complementary recess, and fitting key 7 into the notch in the flange provided therefor. He next swings the two clamping sections together about pivot 13, these sections covering the cope, and, drawing it down tightly, due to the wedging action of the inclined flange surfaces 16. Obviously if there is any dirt or the like between the cope and drag, it will be impossible to swing the clamping sections together, and so the operator is prevented from pouring a casting with these sections relatively displaced. After swinging the clamping sections together the operator positions bar 14 in clamping position and rotates the clamp handle 15 to further wedge these sections tightly together. The molten metal is then poured into the gate and riser cavities 17, filling the mold and substantially filling the gate cavity. After the metal has hardened, the clamp is released and the clamping sections swung apart. This leaves the casting enclosed between the cope and the drag with the metal which was formed in

the gate and riser cavities exposed. Due to the cope being formed in halves, these halves may be removed laterally and the casting lifted out of the drag by the ejecting mechanism.

5 While I have described the illustrated embodiment of my invention with some particularity, it is obvious that many others will readily occur to those skilled in this art, and I, therefore, do not limit myself to the precise 10 details shown and described but claim as my invention all embodiments falling within the scope of the appended claims.

Claims:

1. A mold comprising a plurality of sections and wedging means engaging such sections to hold them tightly together.

2. A mold comprising a plurality of sections, inclined surfaces on some of the said sections, and clamping means engaging said 20 inclined surfaces to wedge and hold the mold sections tightly together.

3. A mold comprising upper and lower mold sections, laterally moving clamping sections, there being inclined surfaces on said 25 mold sections cooperating with inclined surfaces on said clamping sections whereby movement of the clamping sections toward each other wedges the mold sections tightly together.

4. A molding apparatus comprising a base, 30 a drag fixed to said base, a cope fitting thereon, inclined surfaces on one of said mold parts, and laterally movable clamping sections supported on said base and engaging said inclined surfaces when moved together 35 to wedge the drag and cope tightly together.

5. A mold comprising a drag and a divided cope, clamping sections movable to clamp said drag and cope tightly together, and recesses in said clamping sections constituting gate and 40 riser cavities for the mold.

6. A mold comprising a drag and cope, inclined surfaces on one of said sections, the cope being divided diametrically, clamping sections engaging said inclined surfaces to 45 wedge said drag and cope together, the inner surfaces of said clamping sections, when in closed position, constituting gate and riser cavities for the mold.

7. A mold comprising a drag and cope, 50 clamping sections engageable with said mold sections, wedging means carried thereby for tightly holding the mold sections together, and an ejector for removing castings from the mold.

In testimony whereof I hereunto affix my signature this 7th day of June, 1927.

ALLEN B. NORTON.
